(57) **CLAIM**

The ornamental design for a tire tread, as shown and described.

DESCRIPTION

FIG. 1 is a perspective view of a tire tread showing my new design, it being understood that the tread pattern is repeated throughout the circumference of the tire, and that the broken lines illustrate the location of the sidewall and bead, but form no part of the claimed design; and,

FIG. 2 is an enlarged fragmentary plan view of the tire tread illustrated in FIG. 1.
